UNITED STATES PATENT OFFICE.

ACHILLE JOSEPH OISHEI HOSCHEK, OF NEW YORK, N. Y.

TRUSS.

Application filed June 26, 1923. Serial No. 647,848.

To all whom it may concern:

Be it known that ACHILLE JOSEPH OISHEI HOSCHEK, a citizen of the United States of America, residing at New York, in the county of New York and State of New York, has invented certain new and useful Improvements in Trusses, of which the following is a specification.

My invention relates to improvements in trusses for hernia or other defect of the abdomen which needs support.

The principal object of my invention is to provide simple and effective means whereby the use of the ordinary waist encircling belt is rendered unnecessary and the discomfort due to the belt cutting into the muscles when stooping down or bending is obviated.

Other and further objects and advantages will be apparent as the specification is proceeded with.

In the accompanying drawings wherein a preferred embodiment of my invention is illustrated:

Figure 1 is a front view of a person showing the truss applied;

Figure 2 is a rear view thereof;

Figure 3 is a detail view of the abdominal supporting member;

Figure 4 is a detail of the suspender attaching member and stub straps;

Figure 5 is a detail view of the waist band or strap.

Figure 6 is a section on line 6—6 of Figure 5.

Referring more specifically to the drawings wherein like reference numerals refer to similar parts, 5 denotes a waist band or strap adapted to extend about one third way around the waist line of the wearer.

An abdominal supporting member comprising a strip 6, of strong material such as duck extends from the waist line at the front down between the legs and thence upwardly around the muscle of the leg at the rear thereof and thence upwardly toward the waist line and slightly toward one side of the wearer. This abdominal supporting member is provided with a plurality of buckles 7, adjacent its forward upper end which are arranged in a row slightly inclined from the vertical to which the stub straps 8, at the forward end of the waist band 5, connect.

The rear end of the waist band 5, is provided adjacent its upper edge with buttons 9 and 10 to which the rear ends of the suspender

loops 11 and 12 button, the lower edge of the rear end of the band being provided with eyes 13 and 14 with which corresponding hooks 15 and 16 on the rear end of the abdominal supporter 6, connect.

The suspender loop 12, which as previously described connects at its rear extremity to the button 10, is connected at its other end to buttons 17, on the upper front extremity of the abdominal supporter 6. 65 The suspender loop 11, also previously described as being connected at its rear extremity to the button 9, on the waist band 5, is connected at its opposite end to buttons 18, on a strip of fabric 19. This strip of 70 fabric 19, carries a plurality of stub straps 20, of graduated length adapted for attachment to a corresponding member of staggered buckles 21, some of which are secured to the inner edge of the abdominal 75 supporter 6 and others to the extension or flap 22, stitched thereto or forming an integral part thereof.

It will be noted that the stub straps 8, are connected to the supporter 6, substantially midway the point of attachment of the stub straps 20, and the suspender loop 12, also that the stub straps 8 and 20 are respectively connected to opposite sides of the front portion of the supporter. This 85 arrangement together with the fact that the waist band extends but part way around the waist insures freedom of action and an equalization of the various stresses exerted on the supporter by the suspenders and 90 waist band.

Having thus described my invention what I claim is:

1. A device of the kind described comprising an abdominal supporting member 95 extending at the front down between the legs of the wearer and thence upwardly at the rear towards the waist line, a waist band partially encircling one side of the waist line and connected at opposite ends to said abdominal supporting member, a pair of suspender loops and means for connecting opposite ends of said loops respectively to the front and rear portions of said abdominal supporting member.

2. A device of the kind described comprising an abdominal supporting member extending at the front down between the legs of the wearer and thence upwardly at the rear towards the waist line, a waist band 110

extending partially around the waist line and connected at one end to the rear end of the abdominal supporting member, and at its other end connected to the forward part 5 of the abdominal supporting member below the end thereof and at one side, a pair of suspender loops connected at their rear extremities to the rear end of the waist band, the forward extremity of one of said 10 suspender loops being connected to the forward part of the abdominal supporting mem-

ber below and on the opposite side of the waist band connection, and the forward extremity of the other of said suspender loops being connected to the upper forward extremity of said supporting member. 18

In testimony whereof I affix my signature in presence of two witnesses.

ACHILLE JOSEPH OISHEI HOSCHEK.
